UNITED STATES PATENT OFFICE

162,653

PAPER ROLL RACK

Patrick J. Healy, Los Angeles, Calif.

Application May 19, 1949, Serial No. 2,739

Term of patent 14 years

(Cl. D4—3)

To all whom it may concern:

Be it known that I, Patrick J. Healy, a citizen of Canada and a resident of the city of Los Angeles, in the county of Los Angeles and State of California, have invented a new, original, and ornamental Design for Paper Roll Rack, of which the following is a specification, reference being had to the accompanying drawings, forming a part hereof.

In the drawings:

I claim:

The ornamental design for a paper roll rack, substantially as shown.

PATRICK J. HEALY.
